UNITED STATES PATENT OFFICE.

JOHN L. WARING, OF WASHINGTON, DISTRICT OF COLUMBIA.

TONSIL-REMOVING APPARATUS.

Application filed October 12, 1922. Serial No. 594,045.

This invention resides in a novel apparatus and method for the removal of tonsils surgically.

The outstanding advantages of the invention are simplicity of structure, rapidity of operation, and the practically bloodless operation obtained. The apparatus is applicable equally well to general or local throat anesthetic operations. The invention in its broader aspects requires no new apparatus over existing types and may be used with any of the ringed, looped or snare-typed tonsillotomes.

Broadly stated, the invention comprises a tube, having one end formed into a bulbous enlargement, the mouth of the enlargement being tapered somewhat inwardly towards the axis of the mouth. Suction is applied to the other end of the tube. The bulbous end is placed over the tonsil to be removed, and the suction will draw the tonsil from its bed and hold it firmly in the bulbous end of the tube. A snare, or looped wire, is now drawn across the mouth of the bulbous end of the tube so as to pinch or enucleate the tonsil from the throat.

More specifically, the invention is directed to the inward taper of the bulbous portion of the tube. This taper assures the proper operation of the snare or loop by compelling the movement of the wire downwardly and across the tonsil to be removed. In tubes at present in use which do not have the inward taper at the mouth, the snare is liable to slide downwardly of the tube and away from the tonsil.

The invention further has within its province the combination with a tube, of a snare device, the whole forming a convenient and compact apparatus for the removal of the tonsils.

To make the invention more clear, an embodiment thereof has been illustrated in the drawing forming part of this application. The invention in its broad aspects is not, however, to be limited by the drawing. Its scope will be defined in the appended claims.

In the drawings, Fig. 1 is a side view of the apparatus, Fig. 2 is a face view thereof, and Fig. 3 is a face view showing an oval shaped mouth.

Similar reference characters refer to like parts in the figures.

Numeral 1 indicates a tube, made of any desired material. This tube has an end 2 adapted to be connected to a suction device

5, so that a suction may be created in tube 1. The other end of tube 1 is formed into a bulbous enlargement 3 having a mouth 4 which curves inwardly towards the axis of the enlargement, thus forming a mouth of reduced diameter and providing a sloping portion upon which the snare or loop which enucleates the tonsil will slide. Positioned around the bulbous portion 3 in proximity to the downwardly sloping portion 4, is a wire loop or snare 6. The lower portions of the loop, 7 and 8, run through a tube-like element 9 which is attached in any desired manner to tube 1 or formed integrally with tube 1. Emerging from said tube 9, as at 10 and 11, the wire loops around the tube 1 and passes through a hole 12 in the lever 13. Said lever is pivoted at 14 to a bracket 15 attached to tube 1. A spring-like element 16, attached to the lever 17, and abutting against tube 1, serves to hold the lever in its removal position as shown in Fig. 1.

The structure having been set out, its operations will now be described.

Tube 1 is placed in the mouth so that the portion 4 is over the tonsil to be removed. The patient may be under a local or general anesthetic. Suction is applied at end 2 through any desired means, such as a suction pump. The suction created will draw the tonsil from its bed in the throat, and hold it firmly within the bulbous portion 3. The cross section of this portion may be oval or round to suit any particular type of tonsil. With the tonsil thus firmly held, the lever 13 is depressed. This movement of the lever will draw the wires of the loop down through tube 9 and downwardly of the inclined portion 4 of the bulbous part 3 of tube 1. As the depression of lever 13 continues, the wire snare will move completely off portion 4 and downwardly across the tonsil to be removed. As the snare loop is tightened down, the tonsil is practically everted, turned almost wrong side out, and enucleated from the throat clearly, smoothly, and with practically no bleeding or damage to the throat or its structures.

The bulbous portion may, of course, be of any diameter, and the apparatus formed of any material desired. The snare operating portion of the apparatus, need not necessarily be used with the tube, as the tube is adapted to be used with any of the existing forms of snares. The combination of snare

and tube described and shown in this case is, however, held to be a more efficient and convenient apparatus.

Having thus described the invention, I claim:

1. In a tonsil removing device, a tube like element, one end of said tube being adapted for attachment to a suction device, the other end of said tube being bent over and formed 10 into a bulbous portion, said portion curving inwardly towards its mouth whereby a snare may be slipped over the end of the bulbous portion by a pull in a direction at right angles to the bulbous portion.
2. In a tonsil removing device, in combination, a tube having one end formed into a bulbous portion having an inwardly tapering mouth, and a wire snare or loop operative 15 to move downwardly of said taper and across the mouth of said bulbous portion.
3. In a device of the class described, in combination, a tube, one end of said tube being adapted for attachment to a suction creating device, the other end of said tube 20 being formed into a bulbous portion provided with a mouth at one end thereof, a wire snare or loop mounted on said bulbous portion, and means mounted on said tube for drawing the snare or loop across the 25 mouth of said bulbous end.
4. In a device of the class described, in combination, a tube, one end of said tube being formed into a bulbous portion provided 30 with a mouth at one end thereof which tapers outwardly for most of its length, and then tapers inwardly towards the mouth of the tube, a wire snare or loop mounted on said bulbous portion, a lever mounted on 35 said tube, said snare being attached to said lever, a spring-like element to hold said lever in its normal position, said lever when depressed being operative to move said snare along 40 inwardly tapering portion and across the mouth of the tube.
5. In a device of the class described, in combination, a tube of generally tapered form, one end of said tube being adapted 45 to be connected to a suction device, the other end of said tube being bent and forming a bulbous portion provided with a mouth at one end thereof which tapers outwardly for the major portion of its length, and then tapers 50 inwardly towards its mouth for the rest of its length, a wire loop or snare, one end of 55 said loop or snare fitting over the inwardly tapering portion of said bulbous end, a tubular element attached to said tube, said snare running through said tubular element, a lever pivoted on said tube, the other end 60 of said snare encircling said tube and running through one end of said lever, and resilient means to urge said lever to its normal 65 position.
6. As an article of manufacture, a tonsil tube comprising a tube, of generally taper- ing form, one end of said tube adapted to be attached to a suction device, the other end of said tube forming a bulbous bent over portion, said portion tapering inwardly near its mouth whereby a snare may be slipped over the end of the bulbous portion by a pull in a direction at right angles to the bulbous portion.
7. As an article of manufacture, a tube, one end of said tube being of bulbous form, 70 a snare or loop, one end of said snare or loop being mounted on said bulbous end, a lever mounted on said tube, the other end of said snare or loop encircling said tube and attached to one end of said lever.
8. In a tonsil removing device, a gradually tapering tube, one end of said tube being bent at an angle to the tube and formed into a bulbous portion, the end of said bulbous portion tapering slightly inward whereby 75 a snare may be slipped over the end of the bulbous portion by a pull in a direction at right angles to the bulbous portion.
9. A tonsillotome comprising a suction tube adapted to receive a tonsil and means 80 for excising the tonsil attached to said tube to form a unitary structure therewith.
10. In a device of the class described, in combination, a tube, one end of the said tube being adapted for attachment to a suction creating device, the other end of said tube 85 being formed into a bulbous portion provided with a mouth at one end thereof, a wire snare or loop mounted on said bulbous portion, and means mounted on said tube for 90 drawing the snare or loop across the mouth of said bulbous end, at right angles to the axis of the tube.
11. In a device of the class described, in combination, a tube, one end of said tube being formed into a bulbous portion provided 95 with a mouth at one end thereof, which tapers outwardly for most of its length, and then tapers inwardly towards the mouth of the tube, a wire snare or loop mounted on 100 said bulbous portion, a lever mounted on said tube, said snare being attached to said lever, a spring-like element to hold said lever in its normal position, said lever when depressed being operative to move said snare along 105 inwardly tapering portion and across the mouth of the tube, at right angles to the axis of the tube.
12. As an article of manufacture, a tube, one end of said tube being of bulbous form, 110 a snare or loop, one end of said snare or loop being mounted on said bulbous end at right angles to the axis of the tube, a lever on said tube, the other end of said snare or loop encircling said tube and attached to one 115 end of the said lever.

In testimony whereof I affix my signature.

JOHN L. WARING.
